UNITED STATES PATENT OFFICE

HENRY E. BARROLL, OF CHICAGO, ILLINOIS

CONTAINER

Application filed May 14, 1927. Serial No. 191,319.

My invention relates to improvements in cans or containers for fluids and the like and has for one object to provide a new and improved form of container which may be 5 stacked with other containers end to end and wherein there is a permanently installed pouring spout which is protected and which may be used for pouring liquids from the container without the interposition of any 10 additional or removable pouring means. Another object is to provide a new and improved type of container for use with such a spout. Other objects will appear from time to time throughout the specification and claims.

15 My invention is illustrated more or less diagrammatically in the accompanying drawings, wherein—

Figure 1 is a side elevation of two of the containers with parts in section;

20 Figure 2 is a plan view of the container;

Figure 3 is a section along the line 3—3 of Figure 2;

Figure 4 is a detail front elevation;

25 Figure 5 is a diagrammatic view showing the container in use.

Like parts are indicated by like characters throughout the specification and drawings.

A is a generally cylindrical can, slightly tapered so that the outside diameter at the 30 top is a little less than the outside diameter at the bottom. The top and bottom heads of the container are rolled into place in contact with the cylindrical walls as indicated at A¹ and A², there being an upwardly extended flange at the top and a downwardly extended flange at the bottom, the inner diameter of the downwardly extending bottom flange being just sufficiently greater than the outer diameter of the upwardly extending top flange so that one can may stand upon another as indicated in Figure 1, the flanges interlocking to hold the containers in proper position. The top plate A³ has a central boss A⁴ to which a handle A⁵ may be attached.

40 Projecting upwardly from the top plate A³ at a point adjacent the periphery of the container is a spout B. This spout is brazed or welded or otherwise suitably fastened to the plate A³ in permanent relation. The 45 outer side of the spout B is outwardly extend-

ing to form a pouring lip B¹, and laterally extending from the spout is the flange B² surrounding the spout and merging into the pouring lip at a point just inside the periphery of the container. Extending downwardly from the flange B² is an integral collar B³ which in this case is threaded to engage the closure cap B⁴.

The flange A¹ is cut away in front of the spout B and pouring lip B¹ as indicated at C and the wall of the container as at C¹ is bent rearwardly to provide a clearance between the flange and the under edge of the collar B³ so that a receptacle C² may penetrate the space between them to insure that when material is poured from the container, there will be no dropping down the side thereof. Under some conditions, of course it might be sufficient merely to cut the flange away without inward bending but the inward bending is preferable as it adds strength and gives more room for the edge of the container into which liquid is to be poured to penetrate between the room and the collar.

By this arrangement when the cans are stacked, the relatively fragile spout is protected by the flange on the upper container and since the spout terminates at a point below the edge of the rim of the container, it is at all times thoroughly protected.

I claim:

1. The combination with a container having an upwardly extending top flange, of a fixed spout having a laterally extended pouring lip terminating below the flange, the flange being cut away in line with the pouring spout to provide a clearance between the flange and the spout for the edge of the receptacle into which material is to be poured.

2. The combination with a container having an upwardly extending top flange, of a fixed spout having a laterally extended pouring lip terminating below the flange, the flange being cut away in line with the pouring spout to provide a clearance between the flange and the spout for the edge of the receptacle into which material is to be poured, the wall of the container adjacent such cut away portion being inwardly bent to increase such clearance.

3. The combination with a container having an upwardly extending top flange of a fixed pouring spout having a pouring lip terminating below the plane of the flange, the flange being reduced in height adjacent the pouring spout.
4. The combination with a container having an upwardly extended top flange of a fixed pouring spout having a pouring lip terminating below the plane of the flange, the flange being reduced in height adjacent the pouring spout, the spout being laterally extended toward and over the flange adjacent the portion of the flange the height of which is reduced.
5. The combination with a container having an upwardly extended top flange, of a fixed pouring spout positioned adjacent said flange and having a pouring lip terminating below the normal plane of the flange, the portion of the flange adjacent said spout being reduced to a height lower than the plane of said pouring lip.
6. The combination with a container having an upwardly extended top flange, of a fixed pouring spout positioned adjacent said flange and having a pouring lip terminating below the normal plane of the flange, the portion of the flange adjacent said spout being reduced to a height lower than the plane of said pouring lip, the pouring lip extending laterally outwardly beyond such portion of the flange.

Signed at Chicago, county of Cook and
35 State of Illinois, this 6th day of May, 1927.
HENRY E. BARROLL.
